UNITED STATES PATENT OFFICE.

KARL MÜLLER, OF ESSEN-ON-THE-RUHR, GERMANY.

ELECTRIC CONTACT.

Application filed May 17, 1926, Serial No. 109,795, and in Germany May 18, 1925.

In connection with electrical starting devices, it is already known that good results may be obtained when the switch-blade is moved between spring contact pieces. It is known in this case to fasten the contact pieces to the free end of a flat spring member and thereby hold them so that they are swingable. Consequently the contact pieces, in adapting themselves to the movement of the switch-blade, experience an angular rotation, which makes it impossible for a uniform contact to be obtained over the whole surface and further a corresponding non-uniform wear on the contact pieces takes place. Finally, in consequence also of the movement of the switch-blade, a rotation of the contact pieces, though it may only be small, takes place in the direction of motion which also hinders the correct engagement between the contact surfaces and gives rise to premature wear.

The object of the present invention is to enable the contact-blade to make good contact with its opposing metal contact pieces with only a small amount of wear and to ensure a good contact being made even if the contacts are not in exactly the correct position, relatively to the switch-blade.

The invention consists essentially in that the spring-actuated contacts are movably held in a slide guide and therefore the flat contact surface presented by them in any one position remains substantially parallel to this surface when the contact is in another position and can, under the action of the spring, lie freely with its whole surface against the switch-blade.

Two constructional embodiments of the invention are illustrated by way of example in the various figures of the drawings, in which

Fig. 1 is a front elevation of the first embodiment of a starter provided with the new contact pieces with the front wall of the starter cut away,

Fig. 2 is a vertical section on the line II-II of Fig. 1,

Fig. 3 shows a pair of contact pieces in accordance with the invention, together with its guiding means, partly in plan and partly in section on the line A-A of Fig. 4, in about full size,

Fig. 4 is a view seen from the lower side of Fig. 3,

Fig. 5 is a view seen from the upper side 55 of Fig. 3,

Fig. 6 is a view seen from the left-hand side of Fig. 3, and

Fig. 7 is a section on the line B-B of Fig. 3,

Fig. 8 is a side elevation of the second embodiment partly in section on the line A-A of Fig. 9,

Fig. 9 is a plan partly in section on the line B-B of Fig. 8,

Fig. 10 is a cross section on the line C-C of Fig. 8, and

Fig. 11 shows the base-plate of the guide-member in plan.

Referring to the drawings, the holder *c* 70 of the contact pieces is substantially U-shaped in cross-section and its parallel side walls *j* are separated by a central slot *h* in order to allow the contact blade to pass between them. The outer half of each side 75 wall is provided with a guide-slot *b* which is open on the outside. The contact pieces *a* are also of U-shaped cross-section and are so proportioned that the internal distance between the side walls of the holder *c* corresponds with the external distance between the side-walls of the contact pieces *a*. The two contact pieces are inserted in the U-opening of the holder *c* with their bridges facing one another and so that the external 80 projections *a*¹ with which the contact pieces are provided engage in the slots *b*, whereby the contact pieces are guided in a straight line and are prevented by the rear edges of the slots *b* from being pushed beyond the 85 central plane of the holder.

A spring *d* which embraces the contact pieces is inserted in a groove *c*¹ provided in the bottom face of the holder *c*. This spring passes around the holder *c* and engages in the openings of the two contact pieces and lies with its ends against the inner surfaces of the bridges of these contact pieces, so that both contact pieces are pressed towards the central plane of the 100 holder.

The holders of the contact pieces are fastened in series above or beside one another to a plate *o* which is made of slate or other insulating material each by means of a 105 screw *k* and a connecting bolt *m*. A small flexible connector *g* is connected to one of the two projections *a*¹ on each contact piece

and its fork g^1 engages under a clamping screw f on the holder c . Both the holder c and the contact pieces a are made of metal.

The resistances are connected in known manner at the back of the insulating plate o to the connecting bolts m .

The switch blades i are chisel-shaped at both ends and are carried by a metal bridge n . They are in electrical connection with each other. The metal bridge is held in an insulating holder B which is guided by means of two parallel rods t and, in the embodiment illustrated in Figs. 1-4, in the direction in which the blades which are in line follow in succession. In order to drive the bridge and the blades there is provided an endless chain q which is adjusted backwards and forwards alternately by means of a hand-wheel p through suitable gearing. The whole is enclosed by a protective casing u which can easily be opened and from which the hand wheel p projects.

On adjusting the chain the blades are moved in line between each pair of contact pieces. Since the contact pieces are guided at right angles to the path of the blade an equally good contact is always made, even if the contacts or the blades are not exactly in a straight line and have become worn to a different extent. Further, the degree of wear on the surfaces of the contact pieces has no effect on the effectiveness of the contact.

The individual contact pieces can easily be changed since, for this purpose it is only necessary to unscrew the corresponding screw f whereupon the contact-piece can be drawn out backwards from its guide against the action of the spring.

In the embodiment illustrated in Figs. 8-11 the fixed guide-body consists of a substantially H-shaped plate c in the cut-out portions of which the reduced lower ends of the two guide blocks c^1, c^2 engage and are fastened together therewith by means of the two screws k, m to the plate o of insulating material. Each of the guide-blocks c^1, c^2 is provided with a contact piece a which is substantially in the shape of a rectangular tubular member and is guided with its two side pieces a^2, a^3 on the one hand on the corresponding block c^1 or c^2 and on the other hand on the base-plate c . In the inside of the block c^1 or c^2 there is provided a spring-actuated pressure bolt x which tends to press the one contact piece against the opposite contact piece, but its action is limited because the rear wall a^4 of the contact piece abuts against the wall of the block c^1 or the rear head of the pressure bolt x .

For the purpose of conducting the current a flexible connecting band y is connected on the inside of the rear wall a^4 of the contact

piece and is led first downwards and then bent round outwardly and upwards. The band y terminates in a plate z which serves as a pole piece and is fastened by means of a screw f and engages over the upper edge of the side pieces a^2, a^3 that it serves as a guide for the latter.

For the purpose of removing a contact piece only the screw f need be released after which the whole contact piece together with the connecting band y can be lifted upwards. Conversely the replacement also of a new contact piece or the assembly of the contact pieces is extremely simple since the screw f is easily accessible from the top or the front. Consequently in this form of starter the contact pieces can be arranged very closely together and the complete starter may be constructed so as to be extremely compact.

In addition to being employed on starters the new forms of contacts can of course also be employed on other switches, for example, on simple breaking switches, circuit changing switches, separating switches in which case the movement of the switch-blade instead of being from one side of the contact pieces to the other is suitably from above down between the contact pieces. When using such a form of construction as a switch it is advisable for each of the contact pieces to be provided with a horn-shaped extension t illustrated in dotted lines in Fig. 8 in order to exert a blowing action which extinguishes any arcs which may be formed.

I claim:—

1. In an electric switch, a rectilinearly movable switch blade, a rectilinearly movable spring-pressed contact arranged on each side of the line of movement of the blade, each contact having a pair of spaced side pieces and a bridge piece connecting the side pieces and forming a contact plate, a guide for each contact, the said contact plates of the contacts being arranged opposite each other and in parallel relation to each other and the said side pieces of the contacts being in sliding engagement with the guides so as to guide the contacts on straight lines toward or from each other and so as to maintain the contact plates in parallel relationship, and means for slidably moving the switch blade between and across the contact plates of the contacts from side to side of the contacts.

2. In an electric switch, a rectilinearly movable switch blade, a rectilinearly movable spring-pressed contact arranged on each side of the line of movement of the switch blade, each contact being in the form of a rectangular loop and having a pair of spaced side pieces and a bridge piece at each end connecting the side pieces, one of the bridge pieces of each contact forming a contact plate, a guide on each contact and arranged in the space bounded thereby, the said con-

tact plates of the contacts being arranged opposite each other and in parallel relationship to each other and the said side pieces of the contacts being in sliding engagement with 5 the guide members therebetween so as to guide the contacts on straight lines toward or from each other and so as to maintain

their said contact plates in parallel relationship to each other, and means for slidably moving the switch blade between and across 10 the contact plates of the contacts from side to side of the contacts.

In testimony whereof I affix my signature.

KARL MÜLLER.
